UNITED STATES PATENT OFFICE.

CHARLES J. CLOSE, OF COLUMBUS, OHIO

DUMPING-BUCKET.

No. 818,668.

Specification of Letters Patent.

Patented April 24, 1906.

Application filed January 3, 1906, Serial No. 294,362.

To all whom it may concern:

Be it known that I, CHARLES J. CLOSE, a citizen of the United States, residing at Columbus, in the county of Franklin and State 5 of Ohio, have invented certain new and useful Improvements in Dumping-Buckets, of which the following is a specification.

My invention relates to dumping-buckets, especially of the kind adapted to travel in a 10 vertical shaft and to be automatically dumped at a predetermined point, and comprises improved bearing-surfaces for the bucket as it passes up and down the shaft, improved means for causing the bucket to dump, and 15 means for preventing the bucket from tipping too far, whereby it will always right itself when the movement down the shaft is begun.

It also contemplates other features of construction, which will hereinafter be specifically described.

In the accompanying drawings, Figure 1 is a vertical sectional view of a shaft with bucket in place therein. Fig. 2 is a perspective view of the bucket, showing the rollers thereon 25 and the bail by which the bucket is operated. Fig. 3 is a horizontal section through the shaft, showing the bucket in place.

Referring to the drawings, in which the same numerals of reference indicate like parts 30 throughout, 1 and 2 are the front and rear walls of the shaft, in which a bucket 3 is adapted to travel. The side walls 4 and 5 of the shaft are provided each with a flanged guide 6 and 7, secured to the middle thereof 35 and being continuous with the shaft. The bucket is secured pivotally upon a bail 8 at the ends thereof, one being shown at 9, the other not being shown, but constructed in a manner similar to the one illustrated. The 40 bail is formed with a groove in each arm adapted to receive the flanged guides 6 and 7, as appears in Fig. 3. The bail is pivoted near its lower sides on the bucket, so as to cause it to dump automatically whenever the proper 45 opening in the shaft is reached. At its upper side is attached a chain 10, which is drawn around a pulley at the head of the shaft in a well-known manner which need not here be illustrated or described. The guides and 50 grooves hereinbefore mentioned render the ascent and descent of the bucket certain and uniform with respect to the sides, and the front and back of the shaft are provided, preferably, with metallic strips (indicated at 11 and 12) which provide bearing-surfaces for

wheels or rollers 13 and 14, mounted upon the front and back of the bucket, respectively. The rollers render the hoisting of the bucket easier, and there are preferably a plurality both at the front and back. The opening in the shaft is preferably provided with rollers 14^a to facilitate the dumping movement of the bucket.

15 is the dumping-apron.

The stop 16 on the side of the bucket limits 65 the swing thereof rearwardly and assures against dumping on the wrong side of the shaft if perchance there should be an opening therethrough.

On the inside of the shaft opposite the 70 dumping-opening therein is secured a deflector or tipping device 17, which curves upwardly and inwardly. As the bucket is hoisted the rollers 14 reach the deflector, and as they pass along its face the bucket is tilted 75 and the dumping is thereby rendered certain.

To prevent the bucket from turning completely over, as would happen if it were hoisted above the proper dumping position, I provide the chain 18, secured at one end to the 80 bail, at 19, and at the other end to the back side of the bucket, at 20. The length of the chain is sufficient to permit the bucket to assume a horizontal position with respect to the shaft.

As the bucket reaches its maximum dumping position its lower end just clears the point of the deflector extending farthest into the shaft. As the bucket is lowered the front end turns about the rollers on the shaft, and the lower end and rear side pass downwardly 90 along the face of the deflector until the bucket has assumed its normal position on the bail, whereupon it readily descends.

If the motor should be handled improperly 95 and the bucket on account thereof be carried beyond the point intended, it is maintained in its horizontal position by the bail-pivot and the chain and will constantly be held in the proper position to pass the deflector upon descending with its lower end and to come properly into contact with the rollers, whereby the bucket is righted. This construction and arrangement of parts provides against accidents due to careless handling of the 100 hoisting machinery. I obviate the probability of their occurrence as far as possible by operating two buckets simultaneously, the one ascending at the time the other is descending, so that the lowered position of the 105

empty bucket serves to notify the operator that the ascending bucket has reached the dumping-point.

It is apparent from the foregoing description and drawings that I provide a bucket which is adapted to travel smoothly and securely in a shaft on account of the positioning of the ~~bam~~ and the rollers at front and back there. The deflector or curved guide at the back side of the shaft renders the dumping at the proper moment certain. The dumping is further aided by the rollers provided on the shaft at the dump-opening therein. The chain attached to the bail and bucket prevents excessive tipping, and by holding the bucket in a horizontal position prevents any accident or injury to the shaft as the bucket is begun to be lowered. There are no parts required to interlock with each other in order to effect the dumping, as is seen in many dumping devices in use, which arrangement is very likely to result in injury to the parts if the operator is negligent in any degree, and withal the parts are simple in construction and operation and are not readily put out of order.

What I claim as new, and desire to secure by Letters Patent, is—

1. A bucket-dumping device comprising a bucket, a bail pivotally secured to its sides near the bottom thereof, a shaft, vertical guideways for said bucket disposed therein, means for hoisting said bucket in said shaft, the latter having a dumping-opening in the face thereof, means not connected with said guideways on the back side of said shaft opposite the dumping-opening and projecting into said shaft into the path of the bucket, whereby said bucket is caused to assume a dumping position.

2. A bucket-dumping device comprising a bucket, a bail pivotally secured to its sides near the bottom thereof, a shaft, vertical guideways for said bucket disposed therein, means for hoisting said bucket in said shaft, the latter having a dumping-opening in the face thereof, means not connected with said guideways on the back side of said shaft opposite said dumping-opening and projecting

into said shaft into the path of said bucket to overthrow the same outwardly, and flexible means to limit its dumping movement.

3. A bucket-dumping device comprising a bucket, a bail pivotally secured to its sides near the bottom thereof, a shaft, vertical guideways for said bucket disposed therein, means for hoisting said bucket therein, said shaft having a dumping-opening therein, a deflector not connected with said guideways substantially opposite said opening secured to said shaft and projecting into said shaft into the path of said bucket, whereby said bucket is gradually caused to assume a dumping position in said opening, and flexible means passing from said bail to said bucket and connecting the same, and adapted to limit the dumping movement.

4. A bucket-dumping device comprising a bucket, a bail pivotally secured thereto near the lower end thereof, a shaft having a dumping-opening therein, vertical guideways for said bucket disposed in said shaft, means for hoisting said bucket therein, a deflector mounted upon the wall of said shaft substantially opposite said opening, said deflector being curved outwardly into the path of said bucket and adapted to contact with the rear side thereof, to cause said bucket to assume a dumping position in said opening; a flexible connection between said bail and said bucket arranged to control the dumping movement of said bucket.

5. In an elevator-shaft, having a dumping-opening therein vertical guideways, a deflector not connected with said guideways and mounted on the wall of said shaft substantially opposite said opening, said deflector being curved outwardly into the path of a bucket rising in said shaft, and compelling the bucket forwardly to a dumping position by contacting with the rear face of said bucket.

In testimony whereof I affix my signature in the presence of two witnesses.

CHARLES J. CLOSE.
